PORTABLE HAND-OPERATED CUTTING DEVICE

Joe J. Otto, Seattle, Wash.

Application January 15, 1945, Serial No. 572,864

4 Claims. (Cl. 164—73)

This invention relates to what is believed to be an improved cutting device, one which is characterized by certain structural features of refinement and novel phases, the complete arrangement constituting a light weight, portable structure which lends itself admirably well for cutting holes and slots in metal boxes and cabinets, for example, rectangular holes and slots.

I have discovered the need for a feasible and practicable cutting device of the aforementioned type in the electric shop of the plant in which I am employed, in which there is a constant need for cutting holes, that is, rectangular holes and slots, in electrical cabinets. Therefore, the primary object, as above indicated, is the provision of a cutting device to accomplish the results briefly stated, the device being such as to serve in any and all other lines of endeavor in which it will doubtless be found satisfactorily usable.

Briefly, the preferred embodiment of the invention comprises a pair of longitudinally spaced parallel end plates, these adapted to coact with the cabinet or other part to be cut, said plates serving as proper accommodation support for horizontal parallel rods, and said rods serving to accommodate a longitudinally shiftable carriage, the latter provided with the cutting tool and screw-jack means for engaging and disengaging the tool.

Other features and advantages will become more readily apparent from the following description and the accompanying illustrative drawings.

Referring now to the drawings, wherein like numerals are employed to designate like parts throughout the views:

Figure 1 is a top plan view of a special cabinet cutter constructed in accordance with my ideas, the hand crank at the right in Figure 2 being restricted.

Figure 2 is a side elevational view of a fragmentary or contracted-type showing the complete device in readiness for use.

Figure 3 is an elevational view of what may be conveniently referred to as the cutter-equipped carriage unit.

Referring now to the drawings by distinguishing reference numerals, and first to Figure 2, it will be seen that the aforementioned spaced parallel end plates are denoted by the numerals 4 and 5, respectively. The lower inner faces of these plates are provided with outstanding ledge flanges 6 adapted to fit on the cabinet (not shown) or other work to be cut. L-shaped or

angle-type rubber or equivalent cushions 7 are used to provide a suitably cushioned and effective clamping of the plates in place. This clamping action is achieved by a feed-screw 8 whose left hand end is threaded through a screw-threaded hole in the plate 5. The opposite end is provided with shoulder flanges 9 with a journal 10 therebetween to provide a desired turntable operating connection with the plate 4. This end of the feed screw is provided with a suitable hand crank 11 for conveniently adjusting the plates 4 and 5 toward and from each other to fit the job to be undertaken.

I now direct attention to the cylindrical horizontal guide rod 12, there being a pair of such rods and these being screw-threaded and provided with clamping nuts at one end. The nut-equipped ends of these rods, as indicated generally by the numeral 13, are clamped in the upper part of the plate 4. The opposite ends have sliding coaction with smooth-walled holes 14 in the upper end portion of the plate 5. It is to be observed that the feed-screw 8 is almost directly beneath one of these rods 12. Thus, we have, if desired, a single feed screw to work the plates back and forth in an obvious manner. Of course, the plate 5 is actually the movable plate, since this is adjusted toward and from the relatively stationary one 4.

I next call attention to the cutter-equipped shiftable carriage unit generally denoted by the numeral 15 in Figure 3. This comprises a horizontal carriage and shifter plate 16 which stretches across and extends beyond the guide rods 12. The extending end portions are provided with parallel guide barrels 17 which slide back and forth on the rods 12. Said end portions are also provided with suitable outstanding hand-grips 18. The intermediate portion of the plate is provided with cylindrical holes 19. The left hand end portion of the plate is provided with an upstanding internally screw-threaded collar 20, this to accommodate the adjusting screw 21. The upper end of said screw is provided with fine threads and with an appropriate head 22 to facilitate turning thereof. The lower end of the screw is swivelly connected, in any suitable manner, as indicated at 23, with one end of the horizontal adapter plate 24. The latter is in spaced parallelism beneath the main cross-plate 16. This particular plate 24 is provided with upstanding guide pins 25 which extend up and through the accommodation and guide holes 19 in the plate 16. The primary purpose of the adapter plate is to accom-

modate the steel cutting tool 26, this held in place by set screw retained collars 27.

Stop rings 28 and 29 are provided on the end portions of the guide rods 12 to limit the back-and-forth or reciprocatory travel of said tool carriage.

As before stated, the coacting features 6 and 7 provide effective grips and these clamp over the adjacent portions of the cabinet in which the cutting step is to be performed. The adjustment of the plates 4 and 5 to accommodate this is accomplished by the feed screw 8, crank 11 and properly arranged connections between the feed screw and plates. The feed screw and plates, together with the guide rods 12, form an open type framework for the carriage. The carriage is therefore readily shiftable back and forth on the guide rods 12, this through the medium of the conveniently projecting hand-grips 18. The adjustment of the cutting tool 26 is made by the so-called adjusting screw arrangement. In other words, the screw 21 having threaded connection with the plate 16 and swivel connection with the adapter plate 24, serves to raise and lower the cutter with relation to the work, whereby to permit desired results to be properly attained.

The adjusting screw 21 in actual practice is provided with fine threads similar to those used on micrometer adjusting screws. Thus finely regulated adjustments of the cutting points can be had. By contrast, the feed screw is provided with coarse threads, this so that quick adjustment of the device on the job may be readily attained.

Explaining the operation, here is how the device cuts. Let us assume that we have a piece of steel two feet long and eighteen inches wide and we want to cut a hole in it ten inches long and four inches wide. The machine would be set up on this piece of steel with the cutting tool directly over the desired location for one side of the hole and the stops would be set for the ten inch length of the hole. The carriage would now be pushed back and forth, and the cutting tool lowered a little deeper into the cut each time it is pushed until it cuts through the piece of steel. The machine would now be moved over four inches and the other side of the hole cut in like manner. Now, the machine would be turned around cross-ways on the piece of steel with the cutting point directly over end of the hole. The stops 28 and 29 would again be set, this time for the four inch cut and this end of the hole would be cut as before. Finally, the machine would be moved to the other end of the hole and this would be cut in like manner.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a portable hand-operated hole cutter, an open framework embodying a pair of vertical longitudinally spaced and parallel plates, an ad-

justing and clamping screw mounted in said plates to clamp same on the work, a pair of horizontal parallel guide rods also mounted in said plates, a carriage located between said plates and shiftably mounted on said guide rods, a cutting tool, an adapter carrying said cutting tool, and a screw operating connection between the carriage and adapter said screw operating connection serving to vary the depth of cut of said tool.

2. In a framework support for a tool-equipped carriage of the class described, a relatively stationary end plate, said end plate being provided at its top with apertures, a pair of guide rods having threaded ends passing through said apertures, clamping nuts on the threaded ends and clamped against opposite sides of the plate to hold the rods in place, the lower inner surface of said plate being provided with an outstanding flange providing a supporting ledge, a feed screw journaled for rotation in the lower portion of said plate, a hand crank on one end of said feed screw, a second plate opposed in parallelism to the first-named plate, said second plate being provided at its bottom with a ledge flange, the bottom portion being provided with a screw-threaded hole and said feed screw being threaded through said hole, the upper portion of said plate being provided with smooth walled guide openings and said guide rods extending slidably through said guide openings.

3. In a framework support for a tool-equipped carriage of the class described, a relatively stationary end plate, said end plate being provided at its top with apertures, a pair of guide rods having threaded ends passing through said apertures, clamping nuts on the threaded ends and clamped against opposite sides of the plate to hold the rods in place, the lower inner surface of said plate being provided with an outstanding flange providing a supporting ledge, a feed screw journaled

for rotation in the lower portion of said plate, a hand crank on one end of said feed screw, a second plate opposed in parallelism to the first-named plate, said second plate being provided at its bottom with a ledge flange, the bottom portion being provided with a screw-threaded hole and said feed screw being threaded through said hole, the upper portion of said plate being provided with smooth walled guide openings, and said guide rods extending slidably through said guide openings.

4. In a framework support for a tool-equipped carriage of the class described, a relatively stationary end plate, said end plate being provided at its top with apertures, a pair of guide rods having threaded ends passing through said apertures, clamping nuts on the threaded ends and clamped against opposite sides of the plate to hold the rods in place, the lower inner surface of said plate being provided with an outstanding flange providing a supporting ledge, a feed screw journaled for rotation in the lower portion of said plate, a hand crank on one end of said feed screw, a second plate opposed in parallelism to the first-named plate, said second plate being provided at its bottom with a ledge flange, the bottom portion being provided with a screw-threaded hole and said feed screw being threaded through said hole, the upper portion of said plate being provided with smooth walled guide openings, and said guide rods extending slidably through said guide openings, and a carriage unit, said unit being provided with guide barrels slideable on said guide rods, said carriage being provided with adjustable cutter means.

5. As a component part of a portable cutter of the class described, a carriage plate provided at opposite ends with hand-grips, provided inwardly of said ends with guide barrels, said plate being further provided with guide pin holes and a screw-threaded collar, an adjusting screw threaded through said collar, an adapter plate in parallelism beneath the intermediate portion of said first-named plate, said adapter plate having swivel connection with the lower end of said adjusting screw, said adapter plate being further provided with upstanding guide pins extending through the guide pin holes in said carriage plate, and a detachable and adjustable cutting tool carried by said adapter plate.

JOE J. OTTO.
